[57] CLAIM

The ornamental design for a disposable nurser bottle holder, as shown and described.

DESCRIPTION

FIG. 1 is a perspective view of a disposable nurser bottle holder, showing my new design, the broken line showing of the nipple and cap being for illustrative purposes only and forming no part of the claimed design;

FIG. 2 is a top plan view thereof;

FIG. 3 is a front elevational view thereof;

FIG. 4 is a right side elevational view thereof, the left side elevational view being a mirror image;

FIG. 5 is a rear elevational view thereof;

FIG. 6 is a bottom plan view thereof.

FIG. 1.

FIG. 2.

FIG. 5.

FIG. 3.

FIG. 4.

FIG. 6.
